UNITED STATES PATENT OFFICE.

THOMAS N. THOMSON, OF SCRANTON, PENNSYLVANIA, ASSIGNOR, BY MESNE ASSIGNMENTS, TO HOVER-INCUBATOR MANUFACTURING COMPANY, A CORPORATION OF NEW JERSEY.

INCUBATOR.

1,082,980.

Specification of Letters Patent.

Patented Dec. 30, 1913.

Application filed May 3, 1911. Serial No. 624,743.

To all whom it may concern:

Be it known that I, THOMAS N. THOMSON, a citizen of the United States, residing in Scranton, Lackawanna county, Pennsylvania, have invented certain new and useful 5 Improvements in Incubators, of which the following is a specification.

This invention relates to incubators or the like, and aims to provide improvements 10 therein, especially with respect to the humidifying of the air in the incubating chamber. Besides maintaining a uniform temperature of the air within the incubating chamber, it is also desirable to humidify the 15 air, and furthermore, to maintain a uniform humidity.

The object of the present invention is to provide improved means for these purposes.

The invention is preferably incorporated 20 in an incubator having the characteristics set forth in my application for patent, filed April 30, 1910, Serial No. 558,641, (being Patent No. 1,039,844, dated October 1, 1912) and is illustrated as embodied in a form of 25 construction such as illustrated in said application. The invention, however, is not limited in its application to any particular construction of incubator.

The invention will be described more in 30 detail in connection with the accompanying drawings wherein—

Figure 1 illustrates a longitudinal section of a preferred construction embodying my 35 improvements. Fig. 2 illustrates in perspective one of the elements of the invention. Fig. 3 is a fragmentary horizontal section on the plane just above the tray H in Fig 1. Fig. 4 is a view similar to part of Fig. 1 illustrating a modification. Fig. 5 is a fragmentary horizontal section of Fig. 4.

In said drawings A indicates the incubating chamber (parts of which, such as the egg trays, etc., being omitted for clearness), and B indicates, as a whole, any suitable 45 form of heater, but preferably of the construction set forth in my aforesaid application. The heater is provided with an inlet b¹ through which air is admitted to the heater and an outlet b² through which heated air passes to the incubating chamber. Any suitable source of heat may be employed, and as here shown, a lamp C is employed. The heater is provided with a chimney or flue b³, passing through the heater

and open at its top, through which pass the 55 products of combustion. Within the flue b³ is provided a smaller concentric flue b⁴, terminating short of the top of flue b³. The flue b³ further has outlets b⁵ at a lower part thereof. The opening through the top of 60 flue b³ is controlled by a damper F actuated in any suitable manner from a thermostat D within the incubating chamber. As set forth in my aforesaid application, the action of the damper F is to regulate the amount 65 of heat transmitted through the walls of flue b³ in order to raise to an approximately uniform temperature, the air passing through the heater, and thereby maintain the incubating chamber at a uniform 70 temperature.

Adjacent to the inlet to the heater, and preferably within a casing G in communication with such inlet, is a water receptacle or pan H, illustrated in detail in Fig. 2, 75 and preferably shaped to provide a large evaporating surface for the water contained therein. The pan is adapted to be heated directly by the flame or other source of heat, and to that end is preferably provided with 80 a hollow extension h projecting into the interior of the flue b³ above the lamp C. The end of the extension is preferably beveled as at h' in order to present a larger heating surface, and also to facilitate the 85 circulation of the water. The pan H is best made removable from the casing to facilitate cleaning, and is preferably provided with a drain or outlet I through which water may be withdrawn from the pan. 90 Fresh air enters at a over the pan.

It is desirable to provide for the recirculation of part of the air from the incubating chamber through the heater and back to this chamber. For this purpose the bottom 95 of the incubating chamber is preferably provided with an opening O (one or more) communicating with the casing G of the water pan. The opening or openings O are preferably provided with a shutter J, 100 or the like, for regulating the size of the openings, in order to vary the amount of heated air from the incubating chamber admitted to the casing within which the water pan H is contained, the air thus admitted being commingled with the fresh air entering at a. The spent air from the incubating chamber is discharged through 105

any suitable openings into the outer air, as through holes shown in dotted lines at Q Q which discharge outside the casing G, as in my said previous application.

5 In operation, air enters the heater over the pan and, the temperature of the water in the pan being raised by the heater, it readily imparts moisture to the air. The air is then passed through the heater and into the incubating chamber in a moistened condition. The temperature of the water in the pan is maintained approximately uniform by the lamp, inasmuch as for any given interval the flame is a constant one, 10 so that the moisture taken up by the air is practically constant. Moreover, the pan being heated directly by the lamp, it is possible to maintain the water in the pan at a higher temperature than it has heretofore been possible to heat it, thereby insuring a sufficient and plentiful evaporation of the water not only at normal times, but also under considerable variation of surrounding atmospheric temperature. It is also possible to obtain a positive regulation of the moisture evaporated from the pan, by displacing it relatively to the heating element, or even to discontinue the artificial evaporation of the water by removing the pan from 15 the influence of the heater. The preferred means of regulation is by an adjustment of the lamp relatively to the extension h of the water pan whereby the heating effect of the flame upon such extension may be diminished. This is readily accomplished by 20 turning or rotating the entire lamp or the burner thereof around a vertical axis so that for the maximum effect the vertical plane of the flat flame will co-incide with the plane of the extension h, thereby bringing the flame directly beneath the extension, or for a lesser effect the burner may be turned to bring the flame obliquely to (as shown in Fig. 3) or for the minimum effect 25 it may be turned transversely to the extension, whereby in either case a lesser portion of the flame directly plays upon or imparts heat to the extension h. Or the same result may be otherwise obtained as by making 30 the pan H as a slide which can be easily drawn back to partially or entirely remove the extension h from the heating effect of the lamp. This is shown in Figs. 4 and 5 where the pan H may be slid by its handle 35 H' either fully forward, as shown in Fig. 4 or in dotted lines in Fig. 5, to expose the extension h to the maximum heating effect of the flame, or fully backward as shown in full lines in Fig. 5, to so far withdraw the 40 extension h from the lamp flue as to give only the minimum heating effect. To prevent accidentally withdrawing it too far, a stop m is provided; when it is desired to remove the pan altogether, it can be lifted 45 over this stop. Either of these methods of

adjusting the heating effect may be applied with or without the other. Thus the operator can conveniently diminish the humidification or discontinue it entirely as may be required. It is well understood that the maximum humidification is required from the beginning of the incubating period until near its close, and that toward the end of the period the humidification should be diminished to facilitate hatching and to dry the chicks. The openings Q Q may either discharge into the open air, or, as in my previous application, they may discharge the spent air from the incubating chamber into a space around the water-pan as a means of warming the latter and economizing oil. This feature, being clearly shown in my former application and forming no part of my present invention, is not here illustrated in detail.

It is evident that by the present invention a very complete control is had over the evaporation of the water in the water-pan, inasmuch as the heating of the water may be varied at will. This is best done by varying the relations of the water-pan and the lamp flame, as described, but it may be otherwise accomplished, as by varying the heat generated by the heater, or by reducing the depth of water in the pan.

The drawings show the lamp C held in a basin L having inturned fingers q engaging a flange p on the margin of a shell K which is fastened to the bottom of the tube b⁶ of the heater. The shell K is imperforate on one side to protect the wooden casing from heat radiated from the lamp. The basin L is readily applied and removed, and when in place holds the lamp and its font in place, and catches any oil which may leak or ooze therefrom.

The invention is not to be understood as limited to the construction illustrated, as it is obvious that many variations and modifications may be made therein without departing from the spirit of the invention. The specific construction of heater shown is merely illustrative of a suitable embodiment of my invention, and forms no part thereof.

What I claim is:—

1. In an incubator or the like, the combination of a lamp, and a pan having an extension adapted to be heated by said lamp and adapted to be displaced relatively to said lamp, whereby the heating of the water in said extension may be varied or discontinued.

2. In an incubator or the like, the combination of a lamp and a water-pan having an extension adapted to be heated by said lamp, and means for varying the relative positions of the lamp and said extension, whereby the heating effect of the lamp flame upon the water may be varied.

3. In an incubator or the like, the combi-

nation of a lamp and a water-pan having an extension entering the lamp flue, the lamp burner adapted to be rotated to vary the angular position of the flame relatively 5 to said extension, whereby to vary the heating of the water in the pan.

4. In an incubator, the combination of a lamp and an evaporating pan containing water having an extension adapted to project above the lamp for heating the water, 10

and said pan adapted to be displaced longitudinally to vary the heating effect of the lamp.

In witness whereof, I have hereunto signed my name in the presence of two 15 subscribing witnesses.

THOMAS N. THOMSON.
